BOLT-ACTION FIREARM CONSTRUCTION

Frank F. Burton, Mount Carmel, Conn., assignor
to Western Cartridge Company, New Haven,
Conn., a corporation of Delaware

Application March 21, 1939, Serial No. 263,116

5 Claims. (Cl. 42—3)

The present invention relates to improvements in the construction of bolt-action firearms, and relates more particularly to the combination of the breech-bolt and receiver-plug features of such firearms.

As will be apparent from the following considered in conjunction with the accompanying drawings, the present invention is concerned with a construction and organization of parts wherein the receiver of the bolt-action firearm is provided at its rear with a demountable receiver-plug which is coupled to a reciprocating breech-bolt so as to be handable as a unit therewith.

One of the objects of the present invention is to provide a superior bolt-action firearm with a simple and reliable construction and arrangement of parts wherein a removable receiver-plug is employed and wherein a breech-bolt is so constructed and arranged as to be handable as a unit with the said receiver-plug to facilitate the cleaning, inspection and repair of the firearm.

Another object of the present invention is to provide a superior firearm construction embodying a removable receiver-plug, a reciprocating breech-bolt and manually-operable means for actuating the said breech-bolt, all three of which elements are organized together as a unit.

A further object of the present invention is to provide a superior bolt-action firearm construction in which an action-slide is utilized as coupling-means between a breech-bolt and a receiver-plug to thus minimize the number of parts.

Still another object of the present invention is to provide a superior firearm construction wherein the action-slide is supported for reciprocating movement in a manner which assures continued proper functioning and which involves but low cost for manufacture.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a broken view in side elevation of a firearm embodying the present invention and showing the receiver-plug and breech-bolt partly withdrawn from the receiver of the firearm;

Fig. 2 is a view in vertical central-longitudinal section of the receiver and a portion of the barrel and showing the receiver-plug, breech-bolt and

associated parts in side elevation within the said receiver;

Fig. 3 is a transverse sectional view taken on the line 3—3 of Fig. 2;

5 Fig. 4 is a similar view taken on the line 4—4 of Fig. 2;

Fig. 5 is a transverse sectional view taken on the line 5—5 of Fig. 2;

Fig. 6 is a similar view taken on the line 6—6 of Fig. 2;

Fig. 7 is a view in side elevation of the unit comprising the breech-bolt, receiver-plug, action-slide, and associated parts, detached from the firearm;

15 Fig. 8 is a top or plan view thereof;

Fig. 9 is a view in side elevation of the assembly comprising the breech-bolt and action-slide detached;

Fig. 10 is a rear end view thereof;

Fig. 11 is a view in side elevation of the receiver-plug stripped of some of the parts normally organized therewith;

Fig. 12 is a front end view thereof; and

20 Fig. 13 is a perspective view of the action-slide detached.

25 The particular bolt-action firearm herein chosen for the illustration of the present invention includes a stock 20 to which is secured in any approved manner, a receiver 21 and a barrel 22 extending forwardly from the said receiver.

30 The said receiver 21 is of tubular form with its exterior cylindrically contoured, save for certain cuts therein as will hereinafter appear. Furthermore, the said receiver is formed interiorly with an axial cylindrically-contoured bolt-receiving passage 23 which extends throughout the length of the said receiver and at its forward end receives the rear end of the barrel 22 which is rigidly attached to the said receiver in any approved manner such, for instance, as by the threading as shown.

35 Fitting within the rear portion of the bolt-receiving passage 23 is a cylindrically-contoured receiver-plug 24. Intermediate the forward end of the receiver-plug 24 just referred to and the rear end of the barrel 22 is a reciprocating breech-bolt 25 which generally considered is cylindrically contoured, and which is formed at its rear end with an annular bearing-flange 26 and adjacent its forward end with a similar bearing-flange 27.

40 Both of the bearing-flanges 26 and 27 just referred to have a smooth sliding fit within the bolt-receiving passage 23 in the receiver 21, so as to provide both support and guidance for the breech-bolt 25 in its reciprocating movement.

45 50 55

ing movement within the said bolt-receiving passage.

The lower portion of the breech-bolt 25 is formed with a longitudinal passage 28 in which extends the forward end of a spring-guiding plunger 29 having its rear end provided with a head 30 seated in a forwardly-opening socket 31 formed in the receiver-plug 24 and opening through the front face thereof. The socket 31 extends in axial alignment with the longitudinal passage 28 in the breech-bolt 25 and receives the rear end of a helical breech-bolt-return spring 32 which encircles the spring-guiding plunger 29 before referred to. The rear end of the breech-bolt-return spring 32 is seated against the forward face of the head 30 of the spring-guiding plunger 29 and has its forward end seated against the front-end wall of the longitudinal passage 28 in the breech-bolt 25 as is indicated in Fig. 2 of the accompanying drawings.

Above its central longitudinal axis and in parallelism with the longitudinal passage 28, the breech-bolt 25 is formed with a firing-plunger passage generally designated by the reference character 33, and having a relatively-small diametered forward portion 34 opening through the front face of the said breech-bolt and a relatively-large diametered rear portion 35 which latter opens through the rear face of the said breech-bolt.

Mounted for reciprocation within the firing-plunger passage 33 in the breech-bolt 25 is the forward portion of a reciprocating firing-plunger generally designated by the reference character 36, and including a cylindrically-contoured bearing-portion 37 located about midway of its length and bearing in the rear portion 35 of the firing-plunger passage 33 in the breech-bolt 25. Projecting forwardly from the bearing-portion 37 of the firing-plunger 36 is a firing-point 38 adapted to reciprocate in the forward portion 34 of the passage 33. Projecting rearwardly from the bearing-portion 37 of the firing-plunger 36 is a shank 39 of reduced diameter which is adapted to reciprocate in a bore 40 in the receiver-plug 24.

Encircling the shank 39 of the firing-plunger 36 is a helical firing-spring 41 which thrusts at its rear end against the forward face of the receiver-plug 24 and which at its forward end thrusts against the rear end of the bearing-portion 37 of the firing-plunger 36.

The firing-plunger 36 is also formed with a forwardly-facing cocking-shoulder 42 (Figs. 2, 7 and 8) which is engageable by a sear-nose 43 projecting downwardly from the forward end of a sear 44 pivotally mounted by means of a transverse pivot-pin 45 in an upwardly-opening cavity 46 formed in the upper portion of the receiver-plug 24. The said sear 44 may be actuated in any approved manner not requiring detailed description herein, to disengage its sear-nose 43 from the cocking-shoulder 42 of the firing-plunger 36 after the two said features have been engaged by the cocking of the firearm.

The receiver-plug 24 may be secured in place within the rear end of the bolt-receiving passage 23 in the receiver 21 in any suitable manner which will provide for its convenient removal when required, but preferably a reciprocating locking-bolt 47 is employed. The said locking-bolt 47 is mounted for reciprocation in a transverse passage 48 in the rear end of the receiver-plug 24 and is both retained and limited in its reciprocating movement by a vertical pin 49 mounted in the receiver-plug 24 and extending

diametrically through a clearance-passage 50 in the said locking-bolt 47 as is shown particularly well in Fig. 3. The said locking-bolt 47 is of sufficient length to normally have its respective opposite ends entered into locking engagement with locking-passages 51 and 52 formed in the respective opposite side walls of the receiver 21. The locking-passage 51 just referred to is intersected by a longitudinal releasing-passage 53 (Fig. 1) which also intersects the rear end of the receiver 21 and is adapted to provide clearance and free passage for a neck 54 formed upon the adjacent portion of the locking-bolt 47, as is shown in Fig. 3. The locking-bolt 47 is yieldingly retained in the position in which it is shown in Fig. 3 by a helical spring 55 engaging with the pin 49 before referred to.

From the foregoing it will be seen that by manually shifting the locking-bolt 47 from right to left (as viewed in the drawings) against the tension of the spring 55 to bring its neck 54 into registration with the releasing-passage 53, the receiver-plug 24 will be unlocked and may be withdrawn rearwardly out of the rear end of the receiver 21 as may also the breech-bolt 25, as is indicated in Fig. 1.

Inasmuch as the breech-bolt-return spring 32 and also the firing-spring 41 exert a constant effort to axially separate the receiver-plug 24 and the breech-bolt 25, the two latter elements would normally become separated from each other when removed from the receiver 21 in the manner described. To guard against the axial separation of the said receiver-plug 24 and the breech-bolt 25 and to permit the two said units to be handled as a unit, the right side-wall of the said receiver-plug 24 is provided with a longitudinal cavity 56 having a relatively-narrow throat-portion 57 intersecting the front face of the receiver-plug 24. The said throat-portion 57 is adapted to receive and guide with a free sliding fit the rear portion of an action-slide 58 which is preferably formed of sheet metal and which has its forward portion located in a longitudinal groove 59 formed in the side-wall of the rear portion of the breech-bolt 25. The said action-slide 58 is secured to the breech-bolt 25, with capacity for slight pivotal movement, by means of a vertical retaining-pin 60 carried by the said breech-bolt and extending through a suitable perforation in the action-slide 58 adjacent the forward end thereof. At its rear end the action-slide 58 is formed with a depending limiting-finger 61 which is adapted to engage with a rearwardly-facing stop-abutment 62 constituted by that particular portion of the forward wall of the cavity 56 in the receiver-plug 24 which is located immediately below the throat portion 57 therein. The limiting-finger 61 is free to reciprocate within the cavity 56, intermediate the front and rear end-walls thereof, to thus permit the breech-bolt 25 to be manually reciprocated with respect to the normally-immovable receiver-plug 24. The limiting-finger 61 and the cavity 56 thus provide a lost-motion coupling or connection between the said breech-bolt 25 and the said receiver-plug 24.

The action-slide 58 above referred to is also formed adjacent its rear end with a laterally-projecting finger-piece 63 which extends upwardly and slightly rearwardly from the plane of the major portion of the said action-slide 58 and preferably has a knurled and concave forward face, as shown. The base-portion of the said finger-piece 63 is adapted to reciprocate in a

clearance-slot 64 formed in the adjacent side wall of the receiver 21.

When the receiver-plug 24, the breech-bolt 25 and the associated parts are assembled in the receiver 21, the user of the firearm may manually retract the said breech-bolt and the firing-plunger 36 by drawing rearwardly upon the knurled finger-piece 63 of the action-slide 58 against the tensions of the breech-bolt-return spring 32 and the firing-spring 41. The described rearward movement will effect the cocking of the firing-plunger 36 and will effect the ejection of the cartridge-case of the just-fired cartridge preparatory to the introduction of a fresh cartridge into the firearm. Upon releasing rearward draft upon the action-slide 58, the breech-bolt will move forwardly under the urge of the breech-bolt-return spring 32 and assume its breech-closing position while the firing-plunger 36 remains cocked, preparatory to discharging the firearm, in which latter event, the said firing-plunger will reassume the position in which it is shown in the drawings.

When it is desired to remove the breech-bolt 25 and its associated parts, for any purpose such, for instance, as to permit the cleaning and oiling of the parts, the locking-bolt 47 is pressed from right to left to release the receiver-plug 24 in the manner before described herein. As the receiver-plug 24 is moved rearwardly, out of the rear end of the receiver 21, the breech-bolt 25 will lag slightly therebehind until the limiting-finger 61 of the action-slide 58 engages with the stop-abutment 62 in the said receiver-plug. The continued rearward draft upon the receiver-plug 24 will, under the conditions just described, draw with it, by virtue of the coupling action of the action-slide 58, the said breech-bolt 25, together with the parts carried thereby. The assembly or unit as thus withdrawn is shown particularly well in Figs. 7 and 8.

From the foregoing, it will be seen that the breech-bolt 25 and its associated parts may be readily demounted from the firearm structure by the simple act of releasing and removing the receiver-plug 24 and, further, that the parts as thus removed will remain assembled and, therefore, not require elaborate manipulation or adjustment to insure their proper reinstallation into the receiver 21.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A bolt-action firearm-construction, including in combination: a receiver having a longitudinal bolt-receiving passage therein and a longitudinal slot in its side wall and both opening through its rear end; a breech-bolt reciprocatable in the bolt-receiving passage in the said receiver and removable through the rear end thereof; a receiver-plug removably secured within the rear end of the bolt-receiving passage in the said receiver; a releasable spring-pressed locking-bolt movable transversely of and engageable with both the said receiver-plug and the said receiver; a manually-operable reciprocating action-slide extending between the said breech-bolt and the said receiver-plug; first cou-

pling-means connecting a forward portion of the said action-slide to the said breech-bolt and constructed and arranged to hold both thereof against turning movement relative to the other; lost-motion coupling-means connecting a rear portion of the said action-slide to the said receiver-plug and constructed and arranged to hold both thereof against turning movement relative to the other and to permit limited longitudinal movement between the said action-slide and the said receiver-plug; and an operating-handle projecting outwardly from the said action-slide into the longitudinal slot in the said receiver and coacting with the walls of the said longitudinal slot to hold the said action-slide and hence the said breech-bolt and receiver-plug against rotary turning movement relative to the said receiver.

2. A bolt-action firearm-construction, including in combination: a receiver having a longitudinal bolt-receiving passage therein and opening through its rear end; a receiver-plug removably secured within the rear end of the bolt-receiving passage in the said receiver and having a stop-abutment; a breech-bolt located forwardly of the said receiver-plug and reciprocating with respect thereto in the bolt-receiving passage in the said receiver and removable through the rear end of the latter; and a manually-operable reciprocating action-slide coupled to and organized with the said breech-bolt and operable to move with the said breech-bolt in the reciprocating movements thereof, the said action-slide having a limiting-finger engageable with the stop-abutment of the said receiver-plug to limit the axial displacement of the said breech-bolt with respect to the said receiver-plug.

3. A bolt-action firearm-construction, including in combination: a receiver having a longitudinal bolt-receiving passage therein and opening through its rear end, the said receiver also having a substantially-longitudinal clearance-slot extending through its side wall and opening through the rear end of the receiver; a breech-bolt reciprocable in the bolt-receiving passage in the said receiver and removable through the rear end thereof; a receiver-plug removably attached to the rear end of the said receiver in position to block the rear end of the bolt-receiving passage therein; a coupling-member loosely interconnecting the said receiver-plug and the said breech-bolt and serving to hold both thereof against axial separation, the said coupling-member having a portion extending outwardly through the substantially-longitudinal clearance-slot in the side wall of the said receiver and serving in conjunction with the said clearance-slot to restrict the turning movement of the coupling-member and the said breech-bolt and receiver-plug, the outwardly-extending portion of the said coupling-member being retrievable rearwardly with the said coupling-member and out of the open rear end of the clearance-slot in the said receiver; and coupling-means releasably connecting the said receiver-plug to the said receiver and movable relative to both the said receiver and the said receiver-plug to permit the rearward removal of the latter jointly with the said breech-bolt and coupling-member.

4. A bolt-action firearm-construction, including in combination: a receiver having a longitudinal bolt-receiving passage therein and opening through its rear end, the said receiver also having a substantially-longitudinal clearance-slot extending through its side wall and opening

through the rear end of the receiver; a breech-bolt reciprocable in the bolt-receiving passage in the said receiver and removable through the rear end thereof; a receiver-plug removably attached to the rear end of the said receiver in position to block the rear end of the bolt-receiving passage therein; breech-closing spring-means thrusting rearwardly upon the said receiver-plug and forwardly upon the said breech-bolt; a coupling-member loosely interconnecting the said receiver-plug and the said breech-bolt and serving to hold both thereof against axial separation under the urge of the said breech-closing spring-means, the said coupling-member having a portion extending outwardly through the substantially-longitudinal clearance-slot in the side wall of the said receiver and serving in conjunction with the said clearance-slot to restrict the turning movement of the coupling-member and the said breech-bolt and receiver-plug, the outwardly-extending portion of the said coupling-member being retrievable rearwardly with the said coupling-member and out of the open rear end of the clearance-slot in the said receiver; and coupling-means releasably connecting the said receiver-plug to the said receiver and movable relative to both the said receiver and the said receiver-plug to permit the rearward removal of the latter jointly with the said breech-bolt and coupling-member.

5. A bolt-action firearm construction, including in combination: a receiver having a longitudinal bolt-receiving passage therein and opening through its rear end, the said receiver also having a substantially-longitudinal clearance-slot extending through its side wall and opening

through the rear end of the receiver; a breech-bolt reciprocable in the bolt-receiving passage in the said receiver and removable through the rear end thereof; a receiver-plug removably attached to the rear end of the said receiver in position to block the rear end of the bolt-receiving passage therein; breech-closing spring-means thrusting rearwardly upon the said receiver-plug and forwardly upon the said breech-bolt; a firing-member carried by the said breech-bolt; firing-spring means thrusting rearwardly upon the said receiver-plug and forwardly upon the said firing-member; a coupling-member loosely interconnecting the said receiver-plug and the said breech-bolt and serving to hold both thereof against axial separation under the urge of the said breech-closing spring-means and of the said firing-spring means, the said coupling-member having a portion extending outwardly through the substantially-longitudinal clearance-slot in the side wall of the said receiver and serving in conjunction with the said clearance-slot to restrict the turning movement of the coupling-member and the said breech-bolt and receiver-plug, the outwardly-extending portion of the said coupling-member being retrievable rearwardly with the said coupling-member and out of the open rear end of the clearance-slot in the said receiver; and coupling-means releasably connecting the said receiver-plug to the said receiver and movable relative to both the said receiver and the said receiver-plug to permit the rearward removal of the latter jointly with the said breech-bolt and coupling-member.
